FIG 2

CARL ALFREO TIPS
INVENTOR.

BY Luis Casper
ATTORNEY.

UNITED STATES PATENT OFFICE

130,390

DESIGN FOR A TEXTILE FABRIC

Carl Alfred Tips, New York, N. Y.

Application October 23, 1941, Serial No. 103,873

Term of patent 3½ years

To all whom it may concern:

Be it known, that I, Carl Alfred Tips, a citizen of the United States, residing in New York city, in the county of New York, and State of New York, have invented a new, original, and ornamental Design for a Textile Fabric, of which the following is a specification, reference being had to the accompanying drawing, forming part thereof.

Fig. 1 is a plan view of a textile fabric showing my new design, and

Fig. 2 is the reverse side thereof.

I claim:

The ornamental design for a textile fabric, substantially as shown.

CARL ALFRED TIPS.
